CLOTHES BRUSH

Walter Hardy Slaughter, Jr., 4314 Donald Ave.,
San Diego, Calif.

Filed Apr. 15, 1959, Ser. No. 806,511

2 Claims. (Cl. 15—184)

The present invention relates to certain new and useful improvements in a pocket-size bristle-equipped brush which may be conveniently and acceptably carried about in one's coat pocket or a handbag and which provides a practical means by way of which a user may dust and brush lint and the like from the user's apparel or hat, as the case may be.

As may, perhaps, be reasonably evident from the preceding general statement of the nature of the invention, a pocket-type garment and hat brush is not new. As a matter of fact, it is old in the art to provide a hollow case or sheath which functions as an enclosure for the bristle-brush when the latter is not in use and permits the brush to be extended or projected through the open end at which time it then becomes a handle. For example, a typical prior art construction would be that shown in the Dennis Patent 1,111,955. An obvious objective in the instant matter is to structurally, functionally and otherwise improve on the Dennis patent and any similarly constructed and performing projectible and retractable pocket-size brushes representative of the state of the art to which the invention relates.

More specifically, the improvement herein presented is characterized by a hollow shell-like casing or sheath which is open at the bottom to allow the bristles of the extensible and retractable brush to function as desired. The top wall of the casing is specially constructed so that at least one-half portion thereof is slotted. The slot serves to accommodate a folding handle, said handle being pivotally connected to the back of the brush and having novel construction so that when the brush is retracted into the casing and handle is folded to one side, it functions as a retaining latch. On the other hand, when the handle is unlatched and properly positioned on its pivot or hinge connection with the brush-back, it constitutes an actuating member by way of which the brush can be conveniently projected or retracted, as the case may be.

In carrying out a preferred embodiment of the invention, the back, sometimes called the backing or, perhaps, even "head" is formed along the top edge with a groove. This groove is in turn provided at the center with a recess and one end of the actuating handle is hingedly mounted and is cooperable with the groove and recess. That is to say, at least one-half portion of the groove serves to allow the rib along the handle to fold into the groove. The extreme outer end of the handle has a finger-grip which is releasably latched to one end portion of the casing or sheath when the handle is folded to an out-of-the-way position.

Other objects, features and advantages will become more readily apparent from the following description and the accompanying illustrative, but not restrictive, drawing.

In the drawing, wherein like numerals are employed to designate like parts throughout the views:

Fig. 1 is a view in section and elevation illustrating a clothes brush constructed in accordance with the principles of the invention and showing the brush collapsed and

2

folded in full lines and with the operating handle swung to an actuating position in phantom lines.

Fig. 2 is a side elevation of the brush illustrated in Fig. 1 but showing the bristles projected for practical use.

Fig. 3 is a section on the vertical line 3—3 of Fig. 1 looking in the direction of the arrows.

Fig. 4 is a top plan view of the folded ready-to-carry brush seen in Fig. 1.

Referring now to the drawing, the casing or sheath is denoted by the numeral 6 and it is of hollow approximately rectangular form. More specifically, the "hollow" of the casing serves as a receiver or housing for the projectible and retractable brush. The brush comprises an elongated block-like back or body member 8 which is slidable freely in the hollow of the casing and which is provided along what may be called bottom edge 10 with bunches of brushing and dusting bristles 12. Reverting to the casing 6, this may be made from moldable commercial plastics of an appropriate grade and color. In the drawing the top of the casing comprises a substantially solid half-portion 14 at the left. The extreme inner end of this half-portion provides a shoulder 16 as seen in Fig. 4. The edge of this shoulder has a cutaway clearance notch 18 therein as seen in Fig. 1. The right hand end portion 20 (Fig. 4) of the top wall has a central slot 22 formed therein and the lengthwise marginal edges of the slot are beveled to converge downwardly as seen better in Fig. 3. This slot 22 opens through the right hand end of the casing and the upper part of the right hand end is notched as at 24 to provide a shoulder 26 and a slightly convex friction-retaining surface 28.

The enclosed upper lengthwise surface of the brush back 8 is provided with a lengthwise channel or groove 30 and the opposite ends of the groove open through opposite vertical end portions 32 of the back 8. Both half-portions 34 of the groove are substantially rectangular in cross-section to accommodate the operating handle which I contemplate using. Actually, these "half-portions" of the channel or groove are so designated because the central portion of the back is provided with a substantially semi-circular recess or well as at 36. This recess and grooved construction serves to accommodate the unique push-pull and operating handle which I use. This handle comprises a shank 38 and the shank is provided at one end with a lug-like hinging member 40 which is hinged or pivoted on the brush back as at 42. The head is of a shape that it cooperates with the recess or well and also operates through the clearance notch 18 without binding or jamming. The outer end of the shank of the push-pull handle is provided with a special purpose head 44 which is of general rectangular or block-like form and this head serves as a finger grip. The grip is so made that it cooperates in size, shape and purpose with the other parts. That is to say, the shank 38 is such that it swings down into the slot 22 and has bevelled edges to cooperate with the bevels along the edges of the slot. The rib 39 (see Fig. 3) keys itself into the half-portion at the right of the recess in Fig. 1. The shank actually extends through and beyond the open end of this part of the slot so that the head or grip assumes the latchable position illustrated in the drawing. Actually, the head has overhanging end portions 46 which as shown in Fig. 4 abut the friction retaining surface 28 when the finger grip is in the friction-lock or held position see in Fig. 1. In other words, this finger grip swings down into the cutaway notch 24 which becomes a keeper and allows the finger grip to rest against the stop shoulder 26. It follows that the push-pull handle which I now conveniently designate by the numeral 48 may assume the position seen in full lines and dotted lines respectively in Fig. 1. In full lines the bristle-equipped brush has been retracted into

70

the receiver or hollow portion of the enclosing casing 6. Therefore, the grooved part of the block or back 8 is up against the underneath side of the wall 14 and wall portions 20. The operating handle or lever 48 has been folded to the right so that now the hinged lug 40 cooperates with the recess or well 36, the shank 38 rests in the slot 22 and the latching head is in the friction-retained-position as shown being held thereby way of a keeper notch and its components 26 and 28. Assume now that one desires to bring the brush into use and to extend the bristles to the position illustrated in Fig. 2. This is done by catching hold of the finger recesses 50 at the ends of the finger grip 48 and then pushing the grip up in the manner illustrated by the arc line A in Fig. 1. The user continues to swing the lever or handle up until it strikes against the edge 16 which then becomes a stop shoulder. Now, the handle is in a position so that by holding the hollow sheath 6 in one hand and pressing the brush out from the receiver, the shank passes down through the hollow space of the casing until the overhanging end portions 46 of the finger grip 44 lodge themselves in the keeper notches or cutouts 52 illustrated in Fig. 2 advantageously. The brush can be withdrawn and stored away in a reverse manner.

It will be evident from the views of the drawing taken in conjunction with the specification that the concept has to do with a collapsible or extensible and retractable bristle-equipped brush and an enclosing casing or sheath therefor wherein the sheath becomes a handle when the brush is projected in the manner obvious in Fig. 2. Novelty is predicated on the grooved back 8 with the central recess or well 36 which construction serves to accommodate the hinged lug 40 and the fold-away shank with the novel hand grip or head means 44 on the outer end thereof. More specifically, novelty has to do with the latching notch 24 providing the cooperating surfaces 26 and 28 to facilitate friction-locking the hand grip in the folded or out-of-the-way position shown.

To expedite the description and particularly the claims, it is to be pointed out that the aforementioned hollow sheath or casing embodies transverse end walls 54, side walls 56 and is open at 58 at the bottom (considering the views of the drawing). The top wall is actually made up of the components 14 at the left which is one-half the length and the slotted half-portion 20 at the right. The adjacent inner ends of the top wall portions 14 and 20 are spaced apart to provide registration with and constitute portions of the side notches 52 in the upper central portions of the side walls which serve to lodge and accommodate the finger grip 48 when it is in the brush projecting and retaining position, illustrated in Fig. 2.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the invention as claimed.

What is claimed as new is as follows:

1. A pocket-size apparel brush comprising a hollow brush receiving and enclosing sheath having the additional function of a handle, said sheath having side walls, end walls, and a top wall and being open at the bottom, said top wall having an imperforate half-portion and a complemental half-portion provided centrally with a lengthwise slot, said slot being open at its ends, a projectable and retractible brush having a back telescoping and sliding in the hollow portion of the sheath and provided along the bottom with extensible and retractible bristles, and a brush operating and latching handle having an end portion hingedly connected to a median portion of said back, and a shank portion registrable and cooperable with the aforementioned slot, the longitudinal edges of said slot being beveled, the shank of said brush having corresponding bevels matching and cooperating with the first named bevels, said back being provided with a groove opening through at least one end of the back, said groove being adapted to accommodate a keying rib, and said shank being provided along one side with a keying rib which is projectible through the slot and adapted to fold into said groove.

2. The structure defined in claim 1 and wherein said shank is provided at an outer end thereof with an enlargement defining a head-like finger grip, said finger grip cooperating, when the handle is folded, with the adjacent outer end portion of said slot, the adjacent upper end of the end wall of the sheath adjacent to said finger grip having a cutaway notch providing a friction-retaining keeper for said finger grip.
